[57]

CLAIM

The ornamental design for a tire carrier for a van type vehicle, as shown and described.

DESCRIPTION

FIG. 1 is a front perspective view of a tire carrier for a van type vehicle, showing my new design;
FIG. 2 is a front elevational view thereof;
FIG. 3 is a top plan view thereof;
FIG. 4 is a rear elevational view thereof;
FIG. 5 is a bottom plan view thereof;
FIG. 6 is a right hand end elevational view thereof; and
FIG. 7 is a left hand end elevational view thereof.
The broken line representation of a part of a van type vehicle in FIG. 1 is for purposes of illustration only.
